Specification of Letters Patent.

Patented Sept. 1, 1914.

Application filed March 7, 1910. Serial No. 547,643.

To all whom it may concern:

Be it known that I, LUDWIG HOLLAND-LETZ, a citizen of the United States, and a resident of Chicago, in the county of Cook 5 and State of Illinois, have invented certain new and useful Improvements in Cameras, of which the following is a full, clear, and exact specification.

My invention relates to cameras, and is 10 designed to provide new and improved constructions whereby they can be readily and accurately focused, and also whereby the time of exposure can be regulated to a nicety.

In order to teach those skilled in the art 15 how to carry out my invention in its preferred form, I have herein illustrated in the drawings and will describe one specific device in which my invention may be embodied, leaving the statement of the scope of the 20 invention to the generic claims, by which it is defined.

To illustrate my invention, I annex here- 25 to three sheets of drawings, in which the same reference characters are used to designate identical parts on all the figures, of which,—

Figure 1 is a side elevation of a camera embodying my invention; Fig. 2 is a fragmentary plan view of one corner of the 30 same; Fig. 3 is a front elevation of the complete camera; Fig. 4 is a central, sectional view of the rear part of the camera, taken on the line A—A of Fig. 3; Fig. 5 is a sectional view taken on the line B—B of Fig. 35 4 on the interior of the casing proper, but on the line B'—B' of Fig. 6, on the exterior; Fig. 6 is a detail in elevation, partly broken away, of the exposure setting or adjusting mechanism; Fig. 7 is a sectional view on the 40 line C—C of Fig. 5; Fig. 8 is a similar view on the line D—D of Fig. 5; Fig. 9 is a detail in section on the line E—E of Fig. 3; Fig. 10 is a detail in section on the line 45 F—F of Fig. 1.

The camera box comprises the back piece 5, the top 6, bottom 7, side walls 8 and 9, and the lens bed 10, which forms the front of the box when in a closed or folded condition. The bed 10 is pivoted to the bottom 7 at 11, and is provided with side braces 12, which are pivoted thereto at 13, each of which braces is provided with the elongated slot 14, through which extend pins 15 secured to the sides 8 and 9 in such a manner

as to limit the downward movement of the 55 bed 10 about its pivot 11 to a position substantially at right angles to the back 5. The upper ends of the slots 14 terminate in short lateral slots with which the pins 15 engage automatically when the bed 10 is 60 pulled down into unfolded or open position to lock said bed against movement about its hinge 11, the automatic action being secured by reason of the small leaf springs 16 secured to the braces 12 and bearing against 65 the pins 15.

The back 5 may be provided with any suitable plate-holding or film-carrying device. I have illustrated a rectangular frame 17 carrying the customary ground glass 18, 70 which normally closes the opening 19 provided in the back 5. The frame 17 is mounted on leaf springs 20, which are secured to the back 5 in such a manner that a plate holder 21 can be slid under the frame 17 75 and securely held in place by the same. To guide and hold the frame 17 and plate holder 21 in their proper position, a flange 22 is provided around three sides of the opening 19, the fourth side having no flange, 80 and that side of the frame 17 is preferably extended out into a beveled edge, as seen at 23 in Fig. 2. When the plate holder 21 is pushed into position in the back of the camera, it occupies the same space which 85 had been occupied by the frame 17. The ground glass 18 in the frame 17 may be protected by a suitable cover 24 pivoted to the frame 17.

Upon the bed 10 are provided suitable 90 ways or guide rails 25 (see Fig. 3), between which the extension bed-plate 26 is mounted to slide, said bed plate 26 being provided with inwardly opposed grooves 27 adapted to receive the ends of the spring plate 28' 95 secured by the screw bolt 29 to the lens-head frame. The spring plate 28' normally presses the lens-head frame guide-plate 28 against the extension bed-plate 26 to prevent the former from moving, but when it 100 is desired to move the lens-head base-frame on the extension bed-plate 26, the operator simply presses the free ends of the two levers 31 toward each other, and as these levers are secured to rock shafts having flattened 105 portions, the swinging of the levers causes the spring plate 28' to release the pressure on the guide plate 28. The ways 25 extend

substantially the entire length of the bed 10, and the grooves 27 extend the entire length of the extension bed-plate 26, so that the range of movement of the lens-head frame 5 is about twice the length of the bed 10.

Rigidly secured to the bottom 7 within the box are two guide blocks 32, one of which is seen in Fig. 4, while the other is directly opposite, having their upper surfaces 10 and their opposing grooves 33 in exact alignment with those of the extension bed-plate 26 in such manner that the lens-head frame can be moved into the box with the lens-head frame guide-plate engaging said 15 guide blocks. The extension bed-plate 26 is arranged to be moved longitudinally on the ways 25 by turning the knurled disk 34 secured to the shaft 35 suitably journaled on the under side of the bed 10 and having 20 secured to the inner end thereof the spur gear wheel 36 which meshes with the rack 37 provided on the under side of the center of the extension bed-plate 26 and extending its entire length.

Rigidly secured to the lens-head frame base 30 are the two upright, round posts 38, which have their opposing sides provided with vertical slots 38^a into which are snugly fitted the two vertical edges of a square 30 plate 39, which is provided with a central, circular aperture through which extends the lens-tube 40 carrying the lens 41. The plate 39 is capable of being adjusted up and down by sliding in the posts 38, and can be adjusted to either side by sliding the lens-head frame base 30 to either side, which is made possible by providing a slot in the frame 30 for the bolt 29 to pass through. By slightly loosening the nut 42 on the bolt 29, the 40 frame 30 can be slid to either side, and then secured in place by tightening the nut 42.

A suitable frame 43 (see Fig. 4) is provided in the camera box, secured to the top 6, sides 8 and 9, and bottom 7, and is connected by the usual bellows 44 with the lens-carrying plate 39. The bellows 44, at a point just in front of the top 6, is provided with a sight aperture having a cloth extension or hood 46 the outer extremity of 50 which is formed to fit snugly to a person's face about the eyes. The operator, by adjusting the hood 46, which is made of stiff enough material to stand erect, to the eyes, can see the surface within the camera box 55 upon which the view from the lens 41 will be reflected, and by turning the hand wheel 34, can properly focus the picture, as clearly seen in Figs. 1 and 4. If desired, the cover 24 back of the ground glass 18 can be 60 opened, and the operator can look on the ground glass from the rear to adjust the lens to the proper focusing point, but since this particular camera is provided with a curtain or focal-plane shutter, the focusing 65 will in most cases be done on the curtain

within the box by the use of the hood 46 and sight aperture 45.

The sight aperture 45 is always open when the camera is set for taking an exposure, but a door or cover plate 47 closes said aperture 45 automatically by the movement of the trip lever 48 (see Fig. 3), which releases the exposing mechanism. The plate 47 is pivotally mounted, preferably by being secured to a rock shaft 49 pivoted at its ends 70 in the sides 8 and 9, just below the sheet-metal flange 50 secured to the top rail of the frame 43, and has one edge of the cloth curtains 51 secured to its ends, said curtains spanning the space between said ends 75 of the plate 47 and the sight aperture 45, to which the adjacent sides of said curtains are secured. The curtains 51 are of somewhat stiff material, and are arranged to fold inwardly on a central line, as indicated by the dotted line 52 in Fig. 4, which fold divides the curtains into two equal triangles whose free edges 53 are preferably of such length 80 as to equal the distance across the aperture 45 from side to side of the camera when the 90 two curtains are placed end to end, so that when the plate 47 is closed against the lower horizontal edge of the aperture 45, at which edge a straight wire 54 is preferably located in the cloth, the edges 53 of the curtains 51 will be folded and laterally close the possible slit between the free edge of the plate 47 and the edge adjacent the wire 54. To hold the wire at the edge of the aperture 45 95 yieldingly in the position shown in Fig. 4, I provide the leaf springs 53', secured, as shown in Figs. 3 and 4, to the sides 8 and 9, and normally holding the wire in the position shown, but capable of being bent back into the box when it is closed up. 100

Inside of the camera box close to the back 5, is a curtain 55 adapted to entirely close the opening 56 in front of the plate holder 21, and having its lower end secured to the roller 57 and its upper end secured to two 110 tapes 58 wound about the disks 59 rigidly secured on the shaft 60 near the sides 8 and 9, which shaft has its bearings in said sides, as seen in Figs. 4 and 5. One end of the shaft 60 extends some distance outside of 115 the side 8, where it has rigidly secured thereto a small spur-gear pinion 61 meshing with a large spur-gear wheel 62 journaled indirectly on the stub shaft 63 secured in the side 8, as clearly shown in Figs. 5 and 7. Between the gear wheel 62 and the side 8, and journaled on the stub shaft 63, is a gear 120 wheel 64, preferably of the same size as the gear wheel 62, and preferably having an elongated hub upon which the wheel 62 is 125 directly journaled. The wheel 64 is in constant mesh with a small gear pinion 65, preferably the same size as the pinion 61, and said pinion 65 is rigidly secured to the shaft 66, which has its bearings in the sides 130

8 and 9. A long roller 67 is secured on the shaft 66, on which roller is secured the upper end of a curtain 68, whose lower end is secured to two cords 69 adjacent the sides 5 and 9, which cords pass downward around the idlers 70 loosely journaled on the reduced ends of the roller 57, and thence upward to pulleys 67' rigidly secured to the ends of the roller 67, to which pulleys their ends are secured. Thus the curtain 68 and the cords 69 are so arranged about the roller 67 and idlers 70 that when the roller 67, as seen in Fig. 4, is turned on its axis anti-clockwise, the lower end of the curtain 68 will positively move downward, and when the roller 67 is turned clockwise, said curtain 68 will move upward and be wound on the roller 67. It will be noted that the curtain 68, which is up away from in front of the plate holder 21 when the camera is set for an exposure, is between the back 5 and the curtain 55, which occupies the position in front of the plate holder 21, but these curtains may in some cases have their positions 20 interchanged.

The curtain 55 has been described as secured to the roller 57, which is located just above the bottom 7, and the roller 57 is loosely mounted on a shaft 71 having its 30 bearings in the sides 8 and 9, with one end extending outside of the side 8, to which end is secured a knurled disk 72, by means of which the shaft 71 can be turned. A spring-pressed pawl 73 is provided, coöperating 35 with a ratchet 73^a on the shaft 71 on the outside of the side 8, whereby the shaft 71 can be retained at any desired position in its rotation, and an indicator 74 is provided at the end of the shaft 71 on the outside 40 of the side 9 to show the number of turns the shaft 71 has been given. The roller 57 is made hollow to furnish sufficient room for the coiled torsion spring 75 arranged about the shaft 71 and having one of its 45 ends secured to the roller 57 at 76, and its other end secured to the shaft 71 at 77. The spring 75 is so arranged that when it is wound up or put under tension by the turning of the shaft 71, it will tend to pull the curtain 55 downward and wind it upon itself. Obviously, the greater the tension is on the spring 75, as shown by the indicator 74, the more rapidly will the curtain 55 be drawn down when released, and thus the 50 time of the exposure varied when it is followed by the curtain 68.

It will be seen by examining Figs. 4, 5, 7 and 8 that, if the gear wheels 62 and 64 were fastened to rotate together in unison and 55 were free to rotate and the spring roller 57 were turned anti-clockwise, the curtains 55 and 68 would move downward in unison and at a speed to correspond with the winding up of the curtain 55 on the spring roller 57, and the direction of rotation of the

parts, as seen in Figs. 4, 7 and 8, would be as follows: The disks 59, shaft 60 and pinion 61 rotate anti-clockwise; the gear wheels 62 and 64 rotate clockwise; the pinion 65, shaft 66 and roller 67 rotate anti-clockwise. 70

To expose the plate in the plate holder 21, it is necessary to have the curtain 55 moved down some distance before the curtain 68 starts to move downward; and to vary the relative time of starting the downward 75 movement of these two curtains, I provide suitable mechanism between the two gear wheels 62 and 64.

To set the curtains for an exposure, the wheel 62 is turned, by means of the cup-shaped setting disk 78, anti-clockwise until stopped by the pin 79 on the wheel 62 coming in contact with and rocking the crank arm 80 of the rock shaft 49 to its limit, i. e., until the plate 47 is completely open and 80 resting against the sheet-metal partition 81, as seen in Figs. 8 and 4, a spring-pressed pawl 82 being provided to engage the teeth of wheel 62 and retain said wheel in its wound-up or set position. It will be noted 85 that as the gear wheel 62 is being rotated anti-clockwise, the pinion 61, shaft 60 and disks 59 will be rotated clockwise, and the tapes 58 will be wound up upon the disks 59, thus moving the curtain 55 upward. 90

The pawl 82 is rigidly secured on a short rock shaft 83 extending through a bearing sleeve 84 and the side 8 to a short distance inside said side, where a crank arm 85 is rigidly secured thereto. To the free end 100 of the crank arm 85 is pivotally connected the upper end of a connecting rod 86, shown in dotted lines in Fig. 1, whose lower end is bent in a hook shape and has its extremity pivotally connected to the free end of the 105 crank arm 87, shown in dotted lines in Fig. 2, which is rigidly secured to the square shaft 88 provided with a long journal 89 in the bearing 90 secured to the bottom 7. As seen in Figs. 1 and 3, the rod 86 is pro- 110

vided with a shoulder or fixed washer 91, and a helically-coiled expanding-spring 92 arranged around the rod 86 is interposed between said washer 91 and a fixed bracket 93 secured to the side 8, to normally press 115 the rod 86 upward and the pawl 82 into engagement with the gear wheel 62. The square shaft 88 has pivoted to its front end at 94 a square bar 95, which, at the point 96 and throughout the rest of its length, is 120 reduced in cross section so that when a square tube 97 is telescoped over the reduced portion of said rod, the outer surface of said square tube, the larger part of said bar 95 and the square shaft 88 will all be 125 flush, forming one continuous square track extending forward above and parallel to the bed 10 to within a short distance of the free end thereof. The purpose of the hinge 94 in the shaft 88 is, of course, to permit the 130

folding tip of the rod 95 into the camera box when the bed 10 is folded up about its hinge 11 to close the box.

As seen in Fig. 1, the forward end of the 5 square tube 97 extends loosely through a sleeve 98 which is mounted to rotate in the bearing 99, and is provided adjacent one end of said bearing 99 with an upwardly extending arm 100 and with a flange 101 adjacent 10 the other end of said bearing 99, which arm and flange prevent the sleeve 98 from sliding out of the bearing 99, which bearing is integral with the lens-head frame base 30 carrying the lens 41. Thus, it is apparent 15 that while the lens 41 is moved toward and away from the plate holder 21, the sleeve 98 will slide on the tube 97. When the camera is set for an exposure, the arm 100 is turned up anti-clockwise, as seen in Fig. 20 3, against the tension of the spring 102, and is retained in such upturned position by the extension 103 on the frame 104, which is pivoted at 105 to the plate 39. The plate 104 is of circular form and acts as a lever, 25 to which the lens tube 40 is connected by means of the plate 106 and studs 107. The plate 106 has the tube 40 rigidly secured therein by screw threads, and the studs 107 are rigidly secured to the plate 106 in such 30 position that by extending straight forward through holes provided therefor in the plate 39, they can be and are pivotally connected to the frame 104 at 108 about midway the pivot 105 and extension 103. The lens tube 35 40 is arranged to slide forward and backward a short distance, being guided at the forward end by the tube snugly fitting through the aperture in the plate 39, and guided at the rear end by the plate 106 40 being fitted to slide in a suitable casing 109 extending rearwardly from the plate 39, to which it is secured. Thus, it will be understood that as the lens tube 40 moves forward and back the frame 104 will move about its 45 pivot 105 away from and toward the plate 39. Springs 110 are interposed between the plate 106 and the plate 39 about the pins 107, which constantly tend to press the plate 106 back away from the plate 39, and the 50 trip lever 48 is provided to engage the extension 111 on the frame 104 and retain the plate 106 in its forward position against the tension of the springs 110, as seen in Fig. 1. The lever 48 is pivoted at 112 to the plate 55 39, and when the said lever is moved by hand against the tension of spring 113 to release its short end from engagement with the extension 111, the spring 110 will force the lens tube 40 rearwardly until the plate 60 106 contacts with its stop, which stop is formed by the inwardly turned edges 114 of the casing 109. This rearward movement of the lens is to cause it to focus correctly on the sensitized surface at the time of exposure, although it was originally focused

on the curtain 55, which is the same distance in front of the sensitized surface as the distance the lens is moved rearwardly. To set the lens again for focusing, all that is necessary is to swing the trip lever 48 out 70 of the path of the lug 111 as the lens is pulled forward by swinging the frame 104, and then allow it to reengage said lug.

From the description given, it will be seen that if after the camera is set for an exposure, which is the position shown in the drawings, the long end of the trip lever 48 is depressed, the short end of the lever 48 will move away from under the extension 111, the frame 104 and the lens tube 40 will move backward, the arm 100 will swing about its pivot clockwise, as viewed in Fig. 3, the square shaft 88 will be rotated clockwise with the arm 100, the connecting rod 86 will be moved downward against the tension of the spring 92, the pawl 82 will be disengaged from the gear wheel 62, the pinions 61 and 65 and the gear wheels 62 and 64 will be rotated by the action of the spring 75 in the roller 57, and the curtains 55 and 68 will move downward and be stopped in their downward movement by the engaging end of the pawl 115 (which is pivoted at 116 to the gear wheel 64) contacting with the stop 117 formed on the inner wall of the casing 118 which incloses the gearing, as seen in Fig. 8. By reference to Figs. 7 and 8, it will be seen that the pawl 115 has a rearwardly extending tail piece to which one end of a spring 119 is connected, the other end of said spring being connected to a suitable fastening 120 on the gear wheel 64 in such manner as to yieldingly hold the engaging end of the pawl 115 in the path of the stop 117 as the gear wheel 64 rotates. A pin 121 extends laterally from the tail end of the pawl 115 into the arc-shaped slot 122 provided in the gear wheel 62, which pin serves as a part of the operative connection between the gear wheels 62 and 64. The slot 122 is concentric to the axis of both gear wheels 62 and 64, and as the wheel 62 is rotated, the wheel 64 will also be rotated by reason of the pin 121 contacting with the end of the slot 122.

When the gear wheel 62 is turned anti-clockwise, as seen in Fig. 7, the pin 121 will contact with the right-hand end of slot 122, and when said gear wheel 62 is turned clockwise, the pin 121 will tend to contact with the left-hand end of the slot 122, but for the purpose of adjusting the amount of lost motion between the two gear wheels 62 and 64 (and thus regulating the distance between the two curtains), a pin 123 extends laterally into the slot 122 from the base of the setting disk 78, rotatably mounted on the hub of the gear wheel 62 and adjustably locked to said wheel 62 by the pin 124 projecting therefrom engaging one of the

100

105

110

115

120

125

130

notches 125 provided on the disk 78, as seen in Fig. 6. This setting disk 78 is yieldingly held against the gear wheel 62 by means of a coiled expanding spring 126 interposed between said disk 78 and the washer or disk 127 secured to the outer end of the hub of the gear wheel 62, as seen in Fig. 5, so that the disk 78 is free to be pulled out of engagement with the pin 124 against the tension of the spring 126. Thus, it is clear that the pin 123 can be placed in any desired position in the slot 122 by manipulating the adjusting disk 78.

As seen in Fig. 7, it will be noted that the left-hand end of the slot 122 is made narrower for a distance long enough to receive both the pins 123 and 121, while the remainder of said slot 122 is made wide enough to permit the pawl 115 to be turned on its pivot 116 so as to have its engaging end pass out of the path of the detent lever 128 pivoted at 129. The pin 123 is so beveled that when it contacts with the pin 121, it will turn the pawl 115 on its pivot 116 to have its engaging end pass out of the path of the detent lever 128, but when said pin 123 is in the narrow, extreme left-hand end of the slot 122, the pin 121 contacting with the narrow part of the slot 122 prevents the pawl 115 from moving about its pivot, and, obviously, as the gear wheel 64 carrying the pawl 115 is forced around clockwise, the pawl 115 will swing the detent lever 128. The movement of the detent lever 128 about its pivot 129 in the other direction is caused by the action of the helically coiled contractile spring 130 secured thereto and to the casing, and the rate of its movement is controlled by the dash pot 131.

When the indicating mark 132 on the disk 78 is set to register with the character $\frac{1}{2}$ on the disk 127, as seen in Fig. 6, the pin 123 is so positioned in the slot 122 as to cause a one-eighth inch open space between the two curtains 55 and 68, as said curtains are moved downward by the mechanism described; similarly, when the indicating mark 132 is set to register with the character 2 on the disk 127, a two-inch opening will be presented between the curtains 55 and 68 while they move down past the sensitive plate; and when the indicating mark 132 is set to register with the word "full" on the disk 127, the curtain 55 will move down to expose the complete sensitive plate before the curtain 68 starts to move down to cover the sensitive plate, and the time intervening between the instant that the curtain 55 is entirely removed from in front of the sensitive plate and the instant that the curtain 68 starts to cover said sensitive plate is controlled by the dash pot 131 acting on the detent lever 128. Therefore, if the detent lever 128 is partly moved about its pivot

129 anti-clockwise before the pawl 115 engages it, the time of complete exposure of the sensitive plate will be lessened; and to move the detent 128 anti-clockwise about its pivot, I provide a small hand lever 133 pivoted at 134, arranged to engage a curved cam surface on the detent lever 128. The lever 133 is also employed to lock the lever 128 against movement anti-clockwise about its pivot (as in the position shown in Figs. 5 to 8, where it engages the straight surface just beyond the curved cam surface) when the indicating mark 132 is set to any point except the "full" mark on the disk 127, as seen in Fig. 6. Indication marks are provided at 135 arranged in arcs with which the free end of the hand lever 133 is arranged to register for the purpose of setting the apparatus for various exposures, i. e., shorter or longer instantaneous exposures, short time exposures and long time exposures.

The fittings of the joint 94 of shaft 95 and of sleeve 99 on the member 97 are sufficiently loose to permit of the shifting of the lens-carrying frame 30 to either side the required distance without causing any binding of the parts.

From the foregoing description, it will be understood that the tension on the spring 75, as shown on the indicator 74, determines the rapidity of the downward movement of the curtains 55 and 68, and the position of the adjusting disk 78 relative to the gear wheel 62, as indicated by the position of the notch 132 relative to the marked disk 127, determines the size of the opening between the curtains 55 and 68, through which the exposure is made. Thus, if the knurled disk 72 is turned to wind up the spring 75 until the indicator 74 shows the predetermined tension of "4", and the hand lever 133 is moved to register with the "time or slit" indication mark, while the mark 132 is set to register with the character " $\frac{1}{8}$ ", as seen in Fig. 6, the device will be set to give a $\frac{1}{8}$ inch exposure aperture between the curtains 55 and 68 at a "4" tension; obviously, a $\frac{1}{4}$ inch exposure aperture between the curtains at an "8" tension would give substantially the same result. And if the spring 75 is set at a "4" tension, and the hand lever 133 is set to register with the character "1" in the tension "4" column, while the notch 132 is set to register with the "full" mark on the disk 127, the device will be set to give a time exposure of one second; obviously, the same exposure could be attained by setting the spring 75 at a "8" tension and setting the hand lever 133 so as to delay or retard the detent 128 twice as long as when the hand lever 133 is set at the character "1" in the tension "4" column.

When a long time exposure is desired, the

spring 75 may be set at any tension and the hand lever 133 is set to register with the "time or slit" mark, while the notch 132 is set to register with the "full" mark, and 5 the operation of the trip lever 48 will in such event cause the curtain 55 alone to move down and leave a full exposure opening, and the hand lever 133 must be moved by hand about its pivot clockwise a sufficient 10 distance to permit the detent 128 to move out of the path of the pawl 115 to permit the curtain 68 to move down and close the exposure opening.

While I prefer to use the curtain 55 to 15 focus upon, in which case the shiftable lens and the hood are essential, yet I may omit this function and use it without one or both of the aforesaid essential features, as a novel and valuable means of regulating time 20 exposures and preventing the fogging of plates or films in case the camera should be accidentally reset with the lens cap off or a sight aperture open, inasmuch as the two curtains are returned without any aperture 25 between them, whereas a single curtain with one or more apertures cannot be returned without exposing the sensitized surface if it is otherwise unprotected, say, from an uncovered lens.

30 While I have shown and described my invention as embodied in the form which I at present consider best adapted to carry out its purposes, it will be understood that it is capable of modifications, and that I do 35 not desire to be limited in the interpretation of the following claims except as may be necessitated by the state of the prior art.

What I claim as new, and desire to secure by Letters Patent of the United States, is:

40 1. In a camera, the combination with a shallow box, of means for holding a sensitized surface in a certain plane, a lens, a focusing surface, means for focusing the lens upon said focusing surface, a hood located at the top and front of the box and surrounding an aperture through which the focusing surface may be seen, the plane of the aperture being inclined to the plane of 45 said surface, and a plate adapted to close said aperture pivoted at the upper edge thereof and swinging always substantially above the top of the sensitized plate.

45 2. In a camera, the combination with a shallow box, of means for holding the sensitized surface in a certain plane, a lens, a focusing surface, means for focusing the lens upon said focusing surface, a hood located at the top and front of the box and surrounding an aperture through which the 50 focusing surface may be seen, the plane of the aperture being inclined to the plane of said surface, a plate adapted to close said aperture pivoted at the upper edge thereof and swinging always substantially above 55 the top of the sensitized plate, and means

for automatically first moving the plate to close the aperture and then exposing the sensitized surface.

3. In a camera, the combination with a box, of means for holding a sensitized surface in a certain plane, a lens, a focusing surface, means for focusing the lens upon the focusing surface, a hood located at the front of the box and surrounding an aperture through which the focusing surface 75 may be seen, a swinging plate pivoted at one edge of the aperture to open and close the same, and curtains connecting the two edges of the plate adjacent the pivoted edge to the adjacent edges of the aperture. 80

4. In a camera, the combination with a box, of means for holding a sensitized surface in a certain plane, a lens, a focusing surface, means for focusing the lens upon the focusing surface, a hood located at the 85 front of the box and surrounding an aperture through which the focusing surface may be seen, a swinging plate pivoted at one edge of the aperture to open and close the same, and rectangular curtains connecting the two edges of the plate adjacent the pivoted edge to the adjacent edges of the aperture. 90

5. In a camera, the combination with means for holding a sensitized surface in a 95 certain plane, of a lens, a movable exposing curtain between the lens and said plane, a covering curtain, automatic means for first moving the exposing curtain and then the covering curtain, mechanism for regulating the interval of time between the movements of the two curtains to regulate the time of exposure, means for regulating the distance between the rear edge of the exposing curtain and the forward edge of the covering 100 curtain as they move transversely to the sensitized surface, and means for regulating the speed of the movement of said curtains. 105

6. In a camera, the combination with a box, of means for holding a sensitized surface in a certain plane within said box, a lens, a movable focusing surface between the lens and said plane, means for focusing the lens upon the movable focusing surface, a hood located at the top and in front of the 115 box and surrounding an aperture through which the focusing surface may be seen, a plate adapted to close said aperture, and means for automatically moving the plate to close the aperture, removing the focusing 120 surface, causing a relative movement of the lens and sensitized surface to focus the lens upon the latter, and then exposing the sensitized surface. 110

7. In a camera, the combination with a 125 box, of means for holding a sensitized surface in a certain plane within said box, a lens, a movable focusing surface between the lens and said plane, means for focusing the lens upon the movable focusing surface, a 130

- hood located at the top and in front of the box and surrounding an aperture through which the focusing surface may be seen, a plate adapted to close said aperture, and means for automatically moving the plate to close the aperture, removing the focusing surface, shifting the lens so as to focus it upon the plane of said sensitized surface, and then exposing the sensitized surface.
8. In a camera, the combination with means for holding a sensitized surface in a certain plane, of a lens, a movable focusing curtain between the lens and said plane, means for focusing the lens upon the curtain, a covering curtain, and means for automatically shifting the lens so as to focus it upon the plane of the sensitized surface, removing the focusing curtain, and then moving the covering curtain.
9. In a camera, the combination with a box, of means for holding a sensitized surface in a certain plane therein, a lens, a movable focusing curtain between the lens and said plane, means for focusing the lens upon the movable surface, a hood located at the top and front of the box and surrounding an aperture through which the focusing curtain may be seen, a plate adapted to close said aperture, a covering curtain, and automatic means for moving the plate to close the aperture, removing the exposing curtain, and moving the covering curtain.
10. In a camera, the combination with a
- box, of means for holding a sensitized surface in a certain plane therein, a lens, a movable focusing curtain between the lens and said plane, means for focusing the lens upon the focusing curtain, a hood located at the top and front of the box and surrounding an aperture through which the focusing curtain may be seen, a plate adapted to close said aperture, a covering curtain, and automatic means for moving the plate to close the aperture, automatically shifting the lens so as to focus it upon the plane of the sensitized surface, removing the focusing curtain, and moving the covering curtain.
11. In a camera, the combination with a swinging plate held in one direction by a spring, of an exposing curtain, a member the rotation of which controls the movement of said curtain, an arm associated with said plate, a spring tending to move it in one direction, and a pin on said member co-operating with said arm to hold the plate against the resistance of the spring until said member starts to move to make the exposure.
- In witness whereof, I have hereunto set my hand and affixed my seal, this 25th day of February, A. D. 1910.
- LUDWIG HOLLAND-LETZ. [L. S.]
